UNITED STATES PATENT OFFICE.

EDWARD W. SALMON, JR., OF BALTIMORE, MARYLAND, ASSIGNOR TO HULL, SALMON, MFG. CO., INC., OF BALTIMORE, MARYLAND.

FILM-CABINET.

1,400,503.

Specification of Letters Patent. Patented Dec. 13, 1921.

Application filed January 13, 1917. Serial No. 142,330.

To all whom it may concern:

Be it known that I, EDWARD W. SALMON, Jr., a citizen of the United States, residing at Baltimore, State of Maryland, have invented certain new and useful Improvements in Film-Cabinets, of which the following is a specification.

This invention relates to film cabinets.

One object is to provide a cabinet or other container for the storage of films when the same are not in use and which is so constructed as to prevent temperature inside from rising and which is fire-proof irrespective of exterior temperatures.

Another object is to provide a container provided with a plurality of separate compartments and in which there is no metallic connection between the compartments, by virtue of which, the conduction of heat or flame from one compartment to another is prevented in the event of a fire, and whereby each film reel of each compartment is independently protected from heat and fire, so that in the event of ignition of a reel in one compartment, neither the flames nor the heat will spread to other compartments.

Another object resides in the provision of a cabinet or other container for the storage of films when the same are not in use which will protect the films from damage by fire or heat, and which will, at the same time, occupy a comparatively small space in the loft or other structure where the projecting apparatus is located.

A still further object is to provide a cabinet which, while constituting an effectual support and housing for a plurality of reels, is composed of an organization of parts directed particularly to compactness in form of structure, and one which may be easily assembled or disassembled, the various parts of the cabinet being of such construction that the same may be readily replaced in the event of damage or wear.

It is still further designed to provide a cabinet structure adapted to house one or more film reels, each reel being supported in a compartment separate from other reels in the event of a plurality of compartments, the construction of the compartments being such, that any number of compartments may be connected together. Where a two or more reel compartment structure is set up, other compartments may be provided with very

few structural changes, the additional compartments being added preferably in the center, and longer connecting bolts, &c., substituted.

With the above and other objects in view, the present invention consists in the combination and arrangement of parts hereinafter more fully described, illustrated in the accompanying drawings, and particularly pointed out in the appended claims, it being understood that changes may be made in the form, size, proportion and minor details without departing from the spirit or sacrificing any of the advantages of the invention.

In the drawings:

Figure 1 is a vertical sectional view, the reel supporting means being illustrated in dotted lines in its raised position.

Fig. 2 is a vertical sectional view.

Fig. 3 is a top plan view.

Fig. 4 is a horizontal sectional view.

Fig. 5 is a detail perspective view illustrating the manner of spacing the rings which provide for the formation of the various compartments in a multiple compartment structure.

Referring now more particularly to the accompanying drawings, the characters 10 and 11 indicate standards provided at their base with feet 12. The upper ends of these standards are concave, as at 13, for a purpose hereinafter explained.

The standards 10 and 11 adjacent their base may be connected by a pair of vertically spaced members A and B. These members are bolted or otherwise secured to the standards, and each member, adjacent the standards, is formed with a ring-shaped bracket 16; the brackets of the lower member B having inwardly directed flanges 17, which support plates 18. The intermediate portions of these members are connected by a substantially rectangular shaped box 19 provided with a cover 20. The box provides a receptacle for burnt carbons or other materials or elements. This structure is preferably a single casting, the four rings 16 being preferably cast with the rectangular box and the four rings 16 with the plates 18 provide two racks at the ends of the box 19 for the support of carbons or any other articles which it might be desired to support in the racks. The unitary structure embodying the box 19 and the rings 16 is

bolted or otherwise secured to the standards. This supporting structure, consisting of the spaced standards 10 and 11 and the said unitary structure, provides a substantial 5 base structure capable of preventing accidental tilting or upsetting of the cabinet and yet occupying a comparatively small space.

The embodiment of the invention illustrated in the accompanying drawings discloses a cabinet particularly adapted to house four film reels in separate compartments. The particular structure illustrated, 10 consists of a series of compartments C, D, 15 E, and F, each compartment being spaced from adjacent compartments by a relatively thick circular or other sheet of asbestos or other fibrous material 21. The partitioning members are of a diameter slightly greater 20 than the film reels received within the compartments.

An annular casting 22 is supported at each end of the base, each of said castings being formed with a lug 23 provided with 25 an opening 24. These rings or castings 22, in assembling the cabinet, are connected by a bolt 25 which passes through the lugs 23 and the upper ends of the standards 10 and 11.

30 The inner faces 26 of the rings or castings 22, are formed with inwardly directed continuous flanges 27 which embrace the adjacent fibrous partitions 21 and which constitute the end walls of the cabinet.

35 A plurality of supporting rings 28, all preferably of the same construction, are provided, each ring having on one face a continuous flange 29 adapted to embrace the adjacent fibrous partitions 21 at its edge, 40 the reverse face of the disk having a continuous flange 30 of greater width than the flange 29, for a purpose presently explained. These rings, for approximately one-half their circumference, are formed with inwardly directed flanges 31 disposed at right angles to and between the flanges 29 and 30. Each of said rings 28 is formed with laterally directed lugs 32 (Fig. 5) whereby the 45 rings are spaced a sufficient distance to permit of the insertion of the reels in the compartments.

50 A semi-circular plate 33 is inserted between each pair of rings, resting on the aforesaid flanges 30, constituting the bottoms of the compartments, there being a semi-circular sheet of fibrous material 34 placed upon said plates 33. The aforesaid inwardly directed flanges 31 have their inner edges terminating short of the inner 55 surfaces of said semi-annular fibrous sheets 34.

55 Semi-circular, or other closures or covers, are provided for the compartments. As shown, these closures are composed of ar- 60 cuate shaped plates 35 and 36 connected to-

gether by bolts or other fastenings 37 and 38 with fibrous material 39 clamped between the plates by said bolts and maintaining the plates spaced apart so as to obviate a metallic connection between the plates. 70 Said closures are mounted to be swung into and out of closing relation with the compartments. To these ends, the plates 35 having extensions 40 hingedly mounted on a rod 41 supported in lugs 42 on the cabinet, 75 said lugs being preferably formed integral with the rings 28. Each plate 35 has side flanges 43 to overlap the upper peripheral portions of the respective rings 28 and also has end flanges 44. These flanges terminate 80 short of the respective closure plates 36, as shown. Each closure supports a reel supporting and lifting mechanism 39. The reel support is substantially as that shown in my co-pending application No. 44,775, filed 85 August 10, 1915, and a detailed description of said mechanism is thought to be unnecessary.

Should a reel in one compartment become ignited, the reel or reels in the adjacent compartment or compartments cannot become ignited by flame or heat, unless the closures of said compartments are lifted, the base, as well as the closures and sides of the compartments, being protected by flame and heat 90 resisting material and there being no metallic connection between the metal partitions constituting the separate compartments, and no metal exposed in the cabinet to be contacted with by the metal reels. 95

100 It will be understood that one or any number of compartments may be built up, the cabinet being preferably of the sectional type, however, and by virtue of the non-metallic connection between the metal parts 105 of the partitions, the metal parts of the partitions, being spaced from one another by the heat and fire resisting fibrous material, the temperature inside is prevented from rising and the structure made fire-proof 110 regardless of interior or exterior temperatures. The structure provides for perfect insulation, resisting both heat and fire, both from within and from without.

115 In the use of my improved cabinet, spread of fire, if any, from the cabinet to adjoining property, is prevented and the films of one compartment are protected in event of fire in another compartment and all films protected from exterior fire and heat, incident 120 to sun, or temperature from any source and also protected from moisture.

125 The present container or cabinet is equally serviceable for the storage of other goods.

What I claim is:—

1. A film cabinet including a base comprising spaced standards, means connecting the standards intermediate their ends, a plurality of annular metallic members supported by the standards, disks of insulating 130

material supported by said metallic members to provide a plurality of compartments, and a closure for each of said compartments.

2. A film cabinet comprising a base including a plurality of vertical standards, means connecting the standards intermediate their ends and constituting a brace for the standards, an annular metallic member supported by each of the standards at its upper end, a disk constructed of insulating material supported by each of said annular members, spaced rings having flanges disposed to engage said disks to provide a compartment between the disks, and a hinged closure supported by said rings and operating between the rings to close the compartment.

3. A film cabinet consisting of a plurality of vertical standards, a flanged member supported by each of said standards, a disk formed of fire-proof material mounted in the flange of each of said members, a plurality of spaced rings interposed between the disks, a plate mounted between said rings and a closure operating between the rings and hingedly supported by the same.

4. A film cabinet consisting of a base, a plurality of spaced flanged metallic members mounted on said base, disks formed of fire-proof material carried by each of said members, spaced rings interposed between said disks and connected to said members, a plate interposed between said rings and a closure hingedly supported by the

rings and members and operating between the rings and coacting with the plate to 35 form a compartment between the rings.

5. A film cabinet comprising a casing composed of a plurality of compartments whose walls are composed of metallic members and insulating material, the insulating material maintaining the metallic members of each compartment in spaced relation to each other, the metallic members each having spaced flanges, a metallic bottom member supported upon the opposing flanges of adjacent metallic members, insulating material disposed on said bottom members, the metallic members also having inwardly directed flanges whose free edges terminate short of the inner surfaces of said last mentioned insulating members, and a closure for each compartment.

6. A film cabinet comprising a casing composed of a plurality of compartments whose walls are composed of metallic members and insulating material, the insulating material maintaining the metallic members of each compartment in spaced relation to each other, the metallic members each having spaced flanges, a metallic bottom member supported upon the opposing flanges of adjacent metallic members, insulating material disposed on said bottom members, and a closure for each compartment.

In testimony whereof I affix my signature. 65
EDWARD W. SALMON, JR.
